UNITED STATES PATENT OFFICE

157,430

SHRIMP CLEANER

Cyril M. Riha, Atlanta, Ga., assignor to Design Development Corporation, Atlanta, Ga., a corporation of Georgia

Application March 17, 1948, Serial No. 145,187

Term of patent 14 years

(Cl. D22—3)

To all whom it may concern:

Be it known that I, Cyril M. Riha, a citizen of the United States, residing at Atlanta, in the county of Fulton and State of Georgia, have invented a new, original, and ornamental Design for a Shrimp Cleaner, of which the following is a specification, reference being had to the accompanying drawing, forming part thereof.

In the drawing:

Figure 1 is a side elevation of a shrimp cleaner, showing my design the opposite side being the same as the side shown in this figure; and

Figure 2 is a top plan view.

Figure 3 is a bottom plan view.

I claim:

The ornamental design for a shrimp cleaner, as shown and described.

CYRIL M. RIHA.
